FILING CABINET

John H. Page, Muskegon, Mich., assignor to Shaw-Walker Company, Muskegon, Mich., a corporation of Michigan

Application October 24, 1952, Serial No. 316,662

4 Claims. (Cl. 312—308)

1

This invention relates to improvements in filing cabinets, and more particularly to fire insulated cabinets used for housing bookkeeping records, although not limited to such use.

Insulated cabinets have relatively thick walls and are bulky, consequently, it is often inconvenient to obtain access to bookkeeping records when filed in the drawers in the usual position facing the front of each drawer. Moreover, the user often finds it more convenient to refer to the files from one side of the open drawer in which the records are kept.

The principal object of the present invention is to provide novel means for mounting auxiliary filing trays for sliding extension in crosswise position in the cabinet drawers, so as to afford more ready and convenient access to said files when the drawers are open.

A further object of the invention is to provide endwise reversible supporting means for the filing trays so as to permit the files in said trays to face toward either side of the cabinet drawer, as desired, but limiting the extensible movement of the trays when adjusted in either direction.

Other objects and advantages of the invention will appear from time to time as the following description proceeds.

The invention may best be understood by reference to the accompanying drawings, in which:

Figure 1 is a perspective view of an insulated filing cabinet, showing one of the drawers open, and with a filing tray in partly extended position toward one side of the cabinet drawer.

Figure 2 is an enlarged detail vertical section taken transversely of the cabinet drawer, showing a filing tray in fully retracted position in said drawer, as when the drawer is ready to be closed in the cabinet.

Figure 3 is a view similar to Figure 2, but showing the filing tray in fully extended position toward one side of the drawer.

Figure 4 is detail vertical section taken transversely of the filing tray, but with the files removed therefrom.

Figure 5 is an enlarged detail plan view of the reversible pan for supporting the filing tray in the drawer.

Figure 6 is an end view of the pan.

Referring now to details of the embodiment of my invention shown in the drawings, an insulated filing cabinet of conventional construction is indicated generally at 10, with two sliding drawers 11, 11, mounted for extension from the front of the cabinet in any suitable manner, as by a pair of extension slides 12, 12, fixed on

2

opposite sides of each drawer and slidably supported in the cabinet in the usual manner. Each drawer 11 includes low side walls 11a, 11a, to which the slides 12, 12 are connected, but preferably not exceeding the height of said slides.

Each of the drawers has a shallow false bottom, herein formed by a filler pan indicated generally at 13, spaced above the true bottom 14 of said drawer. This filler pan is detachably mounted within the drawer with its main upper surface 15 disposed slightly below the level of the drawer slides 12, 12. An angle bar 17 is attached as by welding along the upper surface of said pan. An inverted shaped rib 18 is attached along the opposite side of said pan, and a Z-shaped retainer bar 19 is attached to said upper surface intermediate and parallel to bar 17 and rib 18, but nearer to the latter. The angle bar 17 preferably extends slightly higher than the rib 18; reinforcing U-shaped ribs 25, 25 may also be secured to the under face of the pan.

The filler pan 13 may also be provided with suitable downwardly extending marginal flanges 20, 21 along its sides and ends respectively, 25 adapted to fit within the adjacent side and end walls of the drawer and being supported on the true bottom 14 of the latter as shown in Figures 2 and 3.

One or more of the file trays, indicated generally at 30, are wholly supported by their respective drawers 11 for extension or retraction in a direction generally transverse to the extensible movement of the drawers on their slides 12, 12. Each tray 30 consists of an upstanding end wall 31, an opposite end wall 32, a bottom wall 33 and a pair of side bars 34, 34, connected between the two end walls. In the form shown, the bottom wall 33 is formed of sheet metal, with a depressed central portion 35, and arched side portions 36, terminated in downwardly extending flanges 37, 37. Said tray provides an open container for a plurality of file folders indicated A in Figures 1, 2 and 3. Since the file folders in each tray are normally arranged for access from one side of the drawer 11, the end wall 31 may, for convenience, be considered as the front wall of the tray, and the opposite end wall 32 may be considered as the rear wall of the tray.

A removable end plate 38 for the files may 50 be inserted at the front of the tray and a follower plate 39 may be used at rear of the tray as usual. The tray is mounted on a carriage indicated generally at 40, provided with roller means for engaging the upper surface of the filler 55 pan 13. In the form shown herein, the carriage

consists of a sheet metal strip 41 extending transversely beneath the depressed central portion 35, and having upwardly arched extensions forming supporting brackets 42, 42 for rollers 43, 43. Said brackets are also connected to the downwardly flanged portions 37, 37 of the pan bottom as is best shown in Figure 4.

The rollers 43, 43 are located nearer the rear than the front end of the tray, in the form shown herein, said rollers being disposed approximately one-third the distance from the rear to the front end of said tray.

An elongated strip of metal, generally Z-shaped in cross section, is secured as by welding along the under face of the carriage 40 between the rollers 43, 43. Said Z-shaped strip forms, in effect, a hook 45 opening toward the front end of the tray, in position to become interengaged beneath the Z-shaped retainer bar 19, fixed on the upper surface of the filler pan as previously described.

The use and operation of the device is as follows:

When the drawer is closed, the file tray normally rests in transverse position therein, with its lower front and rear edges rested against endwise movement slightly below the side walls of the drawer. In the form shown, the rear end of the tray abuts the upstanding angle bar 17, while the front end rests on the rib 18 and on the retainer bar 19 rising from the filler pan.

When the drawer is open, the front end of the tray can be lifted sufficiently to clear the adjacent side wall and slide 12 of the drawer. The tray can then be easily shifted forwardly on its rollers until its hook strip 45 becomes engaged beneath the fixed retainer bar 19 on the filler pan, to limit outward movement of the tray and also hold it against forward tilting, in a position partially extended beyond the tray side of the drawer, as shown in Figures 1 and 3. The position of the rollers near the rear of the tray results in very little effort being required to lift the front end of the tray and roll it forward. The tray can also be swung at varying angles 45 to the side of the drawer, as desired by the operator.

When the operator desires to have the file tray face toward the opposite side of the drawer, the tray is temporarily removed, the filler pan 50 is withdrawn from the drawer, and replaced in reversed end to end position. The tray is then replaced in reversed position on the filler pan so as to be operable in the same manner as before, excepting that it is now accessible from 55 the opposite side of the drawer.

It will also be understood that a plurality of trays, such as two, can be mounted in one drawer, when the latter is of sufficient length.

Although I have shown and described one embodiment of my invention, it will be understood that I do not wish to be limited to the detailed features shown and described, but that various modifications may be made without departing from the spirit and scope of the invention, as defined in the following claims.

I claim:

1. In combination with a filing cabinet, a low sided drawer slidably mounted in said cabinet, a filing tray adapted to fit in said drawer when it is closed, said tray having roller means intermediate its ends affording rolling movement of said tray transversely of the direction of sliding movement of said drawer and also affording horizontal swivelling movement of said tray into varying angles relative to said drawer when the latter is open, and interengaging hook means on said tray and the drawer bottom respectively, for limiting the transverse and angular movement of said tray in extended position over and partially beyond one low side of said drawer when the latter is open.

2. A filing cabinet structure in accordance with claim 1, wherein the roller means are disposed adjacent the rear end of the filing tray.

3. A filing cabinet structure in accordance with claim 1, wherein the lower front and rear edges of the filing tray are normally nested between the side walls of the drawer, but permitting the lower front edge of said tray to be lifted over one low side wall of said drawer for moving the tray to a transversely extended position.

4. A filing cabinet structure in accordance with claim 2, wherein a supporting pan is detachably mounted for endwise reversible adjustment in the bottom of the drawer in supporting relation to said roller means, and said supporting pan carries part of the hook means for limiting the transverse and swivelling movements of the tray relative to one or the other low side of the drawer, depending upon the adjusted position of the pan in the drawer.
